PERMEABILITY TEST CONTAINER

Marion D. Brazier, San Gabriel, Calif., assignor
to Petroleum Engineering Associates, Inc.,
Pasadena, Calif., a corporation of California

Application October 6, 1951, Serial No. 250,129

3 Claims. (Cl. 73—33)

1

This invention is directed to a container principally of value in handling unconsolidated mineral samples as frequently of interest, for example, in petroleum production procedures.

In oil well drilling techniques it is almost always the practice to obtain core samples periodically and at spaced intervals throughout the depth of a well bore. These core samples are subject to various laboratory tests and paleontological examination to develop significant data as to the character of the various formations penetrated by the well bore. This practice is well known and of long extent. Of more recent and presently expanding interest is the similar testing of ditch cuttings, these being mineral fragments removed from a well bore with the drilling fluid.

In many cases core samples or ditch cuttings are unconsolidated. Unconsolidated specimens are relatively soft and very susceptible to deterioration on handling. Heretofore it has been substantially impossible to obtain the above mentioned laboratory data from such unconsolidated samples because of the fairly rugged treatment to which these samples are exposed in sampling, transportation, storage and testing. It is obvious, however, that samples of this nature are equally valuable in plotting the characteristics of a given traverse as the more easily handled consolidated cores or cuttings.

I have now developed a container specifically adapted to sampling, retention and storage of unconsolidated and soft mineral materials which permits the acquisition of suitable samples of such materials and the subsequent testing therefor for permeability, etc. without danger of physical deterioration ordinarily consequent upon their unconsolidated nature.

In accordance with the invention I provide a container comprising a cylindrical member, a fine mesh wire screen affixed across one end of the cylinder, a cap member adapted to be removable held across the other end of the cylinder and having an opening therein giving access to the cylinder, and a second fine mesh wire screen disposed across this opening. This second screen may be affixed to the cap member around the edges of the opening therein or may be held across the cylindrical member by the cap member provided that the screen is removable from the cylindrical member upon removal of the cap member.

An important feature of the container is that it may be used in subsurface sampling. Ordinarily core samples or ditch cuttings are ob-

2

tained at the surface of the well after removing a core from a conventional core barrel or after screening the ditch cuttings from the circulating drilling fluid. However, it is possible with the container described herein and as modified for this particular purpose, to obtain samples of unconsolidated formations directly from the well bore. In such practice the container is inserted in the well bore in suitable carrying means and is driven into the particular unconsolidated formation as by a mechanical means or an explosive charge. In this fashion a sample of the unconsolidated material is enclosed within the container which, upon withdrawal from the formation, is capped as hereinafter described.

The invention will be clearly understood from the following detailed description of the accompanying drawings, in which:

20 Fig. 1 is a sectional elevation of one embodiment of the invention; and

Fig. 2 is a sectional elevation of a somewhat different embodiment of the invention specifically adapted for subsurface sampling.

25 The container shown in Fig. 1 comprises a cylinder 10 preferably of metal and having a fine mesh wire screen 11 affixed across one open end thereof. A cap 12 is adapted to be removably mounted over the other open end of the cylinder 10, the cap and cylinder forming a friction joint as illustrated. The cap may, as an alternative, be removably held on the cylinder by conventional screw threads or a fractional turn retaining means. The manner of affixing the cap is not critical providing it is removable, although for reasons hereinafter made apparent, excessive irregularities in the exterior surface of the cylinder are preferably avoided.

30 The cap 12 has an opening or port 14 therethrough giving access to the interior of the cylinder. In this particular embodiment a second fine mesh wire screen 15 is affixed to the inside face of the cap across the opening 14. The screens 11 and 15 are conveniently affixed to the cylinder and cap respectively by brazing, soldering or the like as indicated at 16 and 17 respectively of the drawing. Preferably the edge of the capped end of the cylinder 10 is beveled to form an annular knife edge 18 which serves the double purpose of facilitating the obtaining of the sample as hereinafter described and of providing a substantially fluid-tight seal with the cap.

35 The interior surface 10A of the cylinder 10 is preferably of rough texture corresponding gen-

erally to conventional knurling. Although such treatment of the interior cylinder surface is not essential, it does have advantages as will be apparent hereinafter.

In using the container of Fig. 1 to obtain a sample of an unconsolidated material at the surface of a well bore, for example, the cap 12 is removed and the cylinder 10 is forced into a body of the designated unconsolidated material with the knife edge 18 facilitating such insertion. It is 10 important that the cylinder enter the sample without unduly rearranging the grain structure thereof, such entry being insured by the leading knife edge. The cylinder is then removed from the body of unconsolidated material retaining the sample therein or, depending upon the characteristics of the material, the excess may be broken away from the exterior of the cylinder. A smooth exterior surface is also desired to facilitate entry of the cylinder in the material and for this reason a friction fit between the cap and the body is preferred.

When the sample is retained within the cylinder in the manner described above, the cap is affixed thereon and the sampling is complete. If any appreciable time interval is to elapse prior to laboratory testing of the sample thus retained, it is desirable to seal the container in airtight means, as is generally conventional in any core sampling techniques.

The container is unique in enabling the acquisition of unconsolidated samples and the testing thereof, the testing being carried out without removal of the sample from the container. Testing of the unconsolidated sample, as for example to obtain the permeability thereof, is made possible by reason of the existence and nature of the fine mesh screen enclosing the open ends of the capped cylinder. The nature of these screens is highly important, it being essential that they be of sufficiently fine mesh to retain the finest particles of the unconsolidated sample. Such particles are commonly known as "silt." A 250 mesh screen is satisfactory for some samples, but a 325 mesh screen is preferred as being sufficiently fine to retain the finest particles of substantially all samples recovered. It is further important that the screen be not so fine as to affect the permeability measurements of the sample. In this respect the screen mesh size should not be appreciably finer than 350 mesh. A mesh size of approximately 325 is thus preferred, having both of the above mentioned factors in mind, since this mesh will retain silt in substantially all samples and will not affect permeability. In addition, this particular mesh size has the further advantage of impermeability to water at small pressure differentials, thereby minimizing undesirable moisture loss from the retained sample.

The desirability of providing the container with a rough interior surface was mentioned above. The purpose of this surface is to obtain a relatively tight seal between the retained sample and the container walls so as to avoid channelling of the fluids used to measure permeability along the container walls. Because of the unconsolidated nature of the samples with which the subject container is used, deformation thereof in accordance with surface irregularities of the container is insured, thereby automatically preventing channelling at this inter-face.

The container as illustrated in Fig. 1 is adapted principally to surface sampling. By very minor modifications thereof, and as illustrated in Fig. 2, 75

the container may be used to obtain samples from the well bore itself without the intervening steps of coring or migration in the drilling fluid.

The container shown in Fig. 2 comprises a cylinder 20 preferably having, as in the foregoing embodiment, a rough interior surface. A fine mesh screen 21 is affixed across one end of the cylinder and a perforate metal plate 22 is affixed across the same end of the cylinder to provide a mechanical support for the screen 21. Many modifications can be made in the container with respect to the relationship between the screen 21 and the metal plate 22, it being essential only that the screen cover the one or more perforations in the metal plate and that the plate be juxtaposed to and so as to protect the screen. The reason why such support is required will be apparent from the description of the use of the container. The opposite end of the cylinder 20 is knife edged as in the foregoing embodiment, and is provided with a removable cap 24 having an opening 25 giving access to the interior of the cylinder and having a fine mesh screen 26 sealed thereacross. A number of semi-flexible fingers 28 are affixed at one end to the inside wall of the cylinder adjacent the knife edged end thereof and are positioned to depend into the cylinder and to normally project inwardly from the wall thereof.

30 In employing the container of Fig. 2 for sub-surface sampling, the container with the cap 24 removed is lowered into the well bore by suitable supporting means and is driven into the particular formation to be sampled, generally on a radius of the bore. The driving force may be furnished by mechanical means triggered by remote control or by an explosive charge in an arrangement similar to a gun perforator. The fingers 28 are, at the moment of insertion of the cylinder, displaced against the walls of the cylinder and come into play as the cylinder is retracted to retain in the cylinder the sample housed therein upon forceful insertion of the cylinder into the formation. The metal plate 22 serves to limit the insertion of the cylinder and is required because in many instances the fine mesh screen 21 is not strong enough to withstand the shock attendant upon the required method of insertion. The plate 22 also forms a convenient anchorage for a cable or other means for withdrawing the cylinder from the formation after the forceful insertion as above described. Upon returning the cylinder thus loaded to the surface, the cap is placed over the appropriate end in the manner above described and the encased sample is ready for handling as in the embodiment of Fig. 1.

60 The container of the invention was designed particularly for use in oil production techniques and particularly in the drilling and logging of oil wells, but will find use with equal facility under any circumstances wherein an unconsolidated mineral sample is desired, and may be satisfactorily characterized by tests performed thereon without removal from the container. It is, of course, apparent in any such procedures that the weight of the acquired sample is important in the measurement of saturation and the like, such weight being easily ascertained by a foreknowledge of the precise weight of the individual containers. Conveniently, when these containers are made in large numbers, the weight is stamped or engraved thereon as being substantially invariant during the life of the container.

I claim:

1. In a device for taking a core sample of a

relatively unconsolidated porous material containing fine particles and for determining the permeability of the sample thus taken, the combination which comprises a rigid tube of uniform interior cross section, one end of the tube being open and adapted for driving into the material to obtain the sample and the interior surface of the tube being rough so as to obtain a relatively tight seal between the contained sample and the tube, and a screen disposed across and affixed to the tube remote from its open end.

2. In a device for taking a core sample of a relatively unconsolidated porous material containing fine particles and for determining the permeability of the sample thus taken, the combination which comprises a rigid tube of uniform interior cross section, one end of the tube being open and adapted for driving into the material to obtain the sample and the interior surface of the tube being rough so as to provide a relatively tight seal between the sample and the tube, and a screen of 250-325 mesh disposed across and affixed to the tube remote from its open end.

3. In a device for taking a core sample of a relatively unconsolidated porous material con-

5
